UNITED STATES PATENT OFFICE.

FREDERICK W. NOLTE, OF VICTORIA, BRITISH COLUMBIA, CANADA.

EYEGLASS-MOUNTING.

1,110,002.

Specification of Letters Patent.

Patented Sept. 8, 1914.

Application filed December 12, 1913. Serial No. 806,276.

To all whom it may concern:

Be it known that I, FREDERICK W. NOLTE, of the city of Victoria, county of Victoria, Province of British Columbia, Canada, have 5 invented certain new and useful Improvements in Eyeglass-Mountings, of which the following is a specification.

This invention relates to eye glass mountings of the type in which the nose guards are 10 mounted on levers pivoted on the bridge ends and provided with forwardly projecting finger grips, and my object is to provide in such a mounting a combination spring and pivot for each nose guard lever which will be 15 very simple, cheap, effective and durable.

I attain my object by forming the nose guard lever and bridge end at each side the one to embrace the other and by forming in the said parts slots lying at an angle to one 20 another. A bent spring with two arms normally tending to spring apart has its arms passed through said slot. The turning of the nose guard lever to bring the slots in the lever and bridge end more nearly at right 25 angles to one another closes the arms of the spring, so that a constant spring pressure is maintained on the nose guard lever.

One embodiment of the invention is illustrated in the accompanying drawings in 30 which—

Figure 1 is a plan view of part of the bridge of the mounting; Fig. 2 a similar view showing a nose guard lever applied to the bridge end; Fig. 3 is a plan view of the 35 underside of the parts shown in Fig. 2; Fig. 4 is a front elevation showing part of the bridge with a lens secured in position.

In the drawings like numerals of reference indicate corresponding parts in the different 40 figures.

1 is the bridge provided with laterally extended ends 2.

3 is a nose guard lever, one end of which has the nose guard 4 formed on or secured 45 thereon, and the other end a finger grip 5. The bridge end and the nose guard are shaped the one to embrace the other. Preferably the nose guard is doubled as shown to embrace the bridge end which is suitably

flattened. In one part of the lever end is 50 formed a slot 6 and a similar slot 7 is formed in the bridge end. These slots, when the mounting is not in place on the nose, lie at an angle to one another. The other part of the nose guard lever has an opening 8 55 formed therein, which is preferably circular in shape as shown, though it might be formed as a duplicate of the slot 6.

9 is a spring which is formed of spring wire bent to form two arms which have a 60 tendency to spring apart. To increase the resiliency, one or more coils are formed in the spring at the bend. The arms of the spring are passed through the slots 6 and 7 and the opening 8, the coil 10 lying close 65 to the nose guard lever. The ends of the springs are preferably slightly bent outwardly to prevent any accidental displacement of the spring after it has been placed in position. It is evident that if the nose 70 guard lever be rocked on the bridge end that the action of the two slots on the arms of the spring tends to force the said arms together, and their resistance to this bending provides the spring tension for the nose guard lever. 75 The spring also serves as a pivot for the nose guard lever, securely holding the latter in place.

From the above description it will be seen that I have devised a mounting which is exceedingly simple and which completely eliminates drilling, tapping or other fine work, so that an efficient mount is obtained at the minimum of manufacturing cost. 80

What I claim as my invention is:—

1. In an eye glass mounting the combination of a bridge having a laterally extended end; a nose guard lever, the bridge end and lever being shaped the one to embrace the other and having each a slot formed therein, 90 the slot in one being at an angle to the slot in the other; and a spring bent to form two arms passing through said slots.

2. In an eye glass mounting the combination of a bridge having a laterally extended 95 end; a nose guard lever shaped to embrace the bridge end, the bridge end and lever having each a slot formed therein, the slot

in one being at an angle to the slot in the other; and a spring bent to form two arms passing through said slots.

3. In an eye glass mounting the combination of a bridge having a laterally extended end with a slot formed therein; a nose guard lever shaped to embrace the bridge end and having a slot formed therein at one side at an angle to the slot in the bridge end and a

round opening in the other; and a spring ¹⁰ bent to form two arms passing through said slots.

Dated at Victoria, B. C., this 3rd day of December 1913.

FREDERICK W. NOLTE.

In the presence of—

A. A. CLAYTON,
F. S. MARTEN.
